ILLUMINATED ORNAMENT

Maxwell T. Richardson, 10 Ingrid Drive,
Toronto, Ontario, Canada

Filed Dec. 3, 1964, Ser. No. 82,901

Term of patent 14 years

(Cl. D29—1)

FIG. 1 is a front perspective view of an illuminated ornament showing my new design;

FIG. 2 is a rear perspective view thereof; and

FIG. 3 is a cross sectional view taken on line 3—3 of FIG. 2 showing the light bulb.

I claim:

The ornamental design for an illuminated ornament, as shown.
